DESIGN FOR A BOTTLE

William Guyer, New York, N. Y., assignor to Schenley Products Company, Inc., New York,
N. Y., a corporation of New York

Application January 11, 1934, Serial No. 50,372

Term of patent 14 years

To all whom it may concern:

Be it known that I, WILLIAM GUYER, a citizen of the United States, residing at New York city, in the county and State of New York, have invented a new, original, and ornamental Design for a Bottle, of which the following is a specification, reference being had to the accompanying drawing, forming a part thereof,

Figure 2 is a rear elevation thereof; and Figure 3 is a side elevation thereof.

I claim:
The ornamental design for a bottle as shown.

WILLIAM GUYER.
